CLAIM

The ornamental design for a beverage bottle with lid, as shown and described.

DESCRIPTION

FIG. 1 is a front perspective view of the beverage bottle with lid showing our new design;

FIG. 2 is a rear perspective view thereof;

FIG. 3 is a front view thereof;

FIG. 4 is a left side view thereof;

FIG. 5 is a right side view thereof;

FIG. 6 is a rear view thereof;

FIG. 7 is a top view thereof; and,

FIG. 8 is a bottom view thereof.

The broken lines showing in the figures are included for the purpose of illustrating portions of the beverage bottle with lid that form no part of the claimed design.

1 Claim, 5 Drawing Sheets
